US0D1070366S

(12) United States Design Patent (10) Patent No.: US D1,070,366 S
(45) Date of Patent:  Apr. 15, 2025

(54) SHEET MATERIAL(71) Applicant: SCHATTDECOR AG, Thansau (DE)(72) Inventor: Christian Zaha, Traunstein (DE)(73) Assignee: SCHATTDECOR AG, Thansau (DE)() Term: 15 Years(21) Appl. No.: 29/796,863(22) Filed: Jun. 28, 2021*Related U.S. Application Data

(62) Division of application No. 35/509,157, filed on Apr. 3, 2020 (U.S. filing date under 35 U.S.C. 384), and having an international filing date of Apr. 3, 2020, now Pat. No. Des. 927,858.

(51) LOC (15) Cl. ..... 05-06(52) U.S. Cl.USPC ..... D5/43(58) Field of Classification Search

USPC ... D5/1, 2, 3, 4, 7, 8, 20, 32, 37, 43, 44, 47, D5/55, 56, 58, 59, 60, 62, 99; D25/138, D25/140, 149, 150, 151, 156; D19/1, 5 CPC E04F 13/0871; B44F 1/00; B44F 9/02; B27K 5/02; C04B 28/04; E04C 2/12; B44B 5/0004

See application file for complete search history.
